1

This invention relates to a device comprising a movable member which is provided with a profiled edge which cooperates with the end of a projecting lug.

It has been suggested before to provide devices, such as switching clocks, in which a movable component member is provided with a profiled edge which extends substantially parallel to the direction of movement of the said component member and cooperates with the end of a projecting lug in such manner that during the movement of the component member along a certain portion of the path the end of the lug is moved, under the influence of a force acting on the lug, in a direction substantially perpendicular to the direction of movement of the component member.

In this case, the movable member may be constructed as a cam disc. It is often desirable that at a given position of the disc the lug should perform a sudden movement normal to the edge of the disc. In the known constructions this is realised by providing the profiled edge with a re-entrant part where the end of the lug suddenly falls in under the action of a spring. The lug is then raised and the spring stressed over a generally direct-connecting portion of the profiled edge. For this purpose, the slope of this portion must not be excessive, because the lug would not otherwise be raised. In addition, in this case the supply of the energy required for stressing the spring would ensue through an excessively small angle of rotation of the disc and this is impossible in connection with the generally low available driving couple. This causes a limitation with regard to the choice of the speed of raising and hence of the retracting movement of the lug.

The invention provides a construction by which the said disadvantages are obviated and other advantages can also be achieved.

According to the invention, the lug is moved back into its original position by an auxiliary lug coupled to the projecting lug and cooperating in an identical manner with the profiled edge of a movable auxiliary member under the influence of a force acting on the auxiliary lug. The retracting movement of the lug can be adjusted at will by the shape of the edge of the auxiliary member. If desired, it may be brought about rapidly and even suddenly. As will appear hereinafter, in this case the supply of the energy required for stressing the springs associated with the lugs may be extended over a large portion of the path of the members to be moved, without

any limitation as regards the speed of the retracting movement of the lug resulting therefrom.

In some cases, the retracting movement of the lug must be in a given relation to the forward movement, for example be effected after a given time period or after a certain angular rotation of a movable shaft. For this purpose, in a preferred embodiment of the device according to the invention the component member and the auxiliary member are ganged. A further simplification may thus be achieved in some cases by making the component member and the auxiliary member integral with each other.

In a further advantageous embodiment of the invention a simplification is achieved due to the fact that the lug and the auxiliary lug are rotatable about the same axis, the auxiliary lug carrying the lug along with it, on continued rotation in one direction, by means of a stop.

20 In a further advantageous form of construction of the device according to the invention, which is particularly suitable when the lug has to perform a periodical movement, the component member and the auxiliary member are constructed as cam discs and are rotatably arranged.

25 In a further preferred embodiment of the invention, under the influence of the force acting on the lug and due to the slope of the profiled edge, the lug moves the component member and the auxiliary member until the auxiliary lug becomes operative and moves the lug back into its original position. In this case, it is impossible to give the component member or the auxiliary member such a position that the auxiliary lug 30 remains constantly out of its off-position. As will appear hereinafter, this construction may be used with advantage *inter alia* if a sudden rapid reciprocating movement of a component member is required.

35 40 In a further advantageous form of construction of the device according to the invention the profiled edges of the component member and the auxiliary member are constructed in such manner that in the case of a progressive movement of the component member the end of the lug suddenly performs a movement normal to the direction of movement of the component member and in the case of a continued movement of the auxiliary component member is suddenly moved back 45 by the auxiliary lug into its original position. This construction has a particular advantage when used in connection with contacts that have to be capable of being suddenly put into and suddenly cut out of circuit.

45 50 55 In order that the invention may be clearly

understood and readily carried into effect, it will now be described more fully with reference to the accompanying drawings, in which:

Figs. 1 to 3 inclusive show a form of construction of a device according to the invention in three successive positions.

Figs. 4 and 5 show forms of construction of devices according to the invention.

Fig. 6 is a diagram of an electric device in which the movable contact is controlled by the mechanism shown in Fig. 5.

Referring to the embodiment shown in Figs. 1, 2 and 3, 1 designates the movable component member. It is provided with a profiled edge 2 which cooperates with a lug 3 of a lever 4. During the movement of the member 1 in the direction of the arrow A the lug 3 of the lever 4 falls under the action of a spring 5 behind the re-entrant part 6 of the profiled edge 2. This position is shown in Fig. 2. According to the invention, the lever 4 can be moved back to its original position by an auxiliary lever 7. The latter cooperates with the profiled edge 8 of the auxiliary member 9. This auxiliary member moves in the direction of the arrow B simultaneously, or not, with the movement of the component member 1. When the auxiliary member has moved in the direction of the arrow B to such an extent that the re-entrant part 10 of the profiled edge 8 passes by the end 11 of the auxiliary lever 7 the latter is moved downward under the action of the spring 12. This position is shown in Fig. 3. In this case, according to the invention, the auxiliary lever carries the lever 4 along with it until it has reached its off-position. This is brought about here due to the fact that the lever 7 is provided with an extension 13 which cooperates with a hook-like portion 14 of the lever 4. The spring 12 is more powerful than the spring 5, so that the lever 4 is moved by the lever 7 against the action of the spring 5 to its off-position. If desired, the spring 5 can be replaced by a compression spring arranged between the lever 4 and the auxiliary lever 7. In this case, the power of one spring may be chosen independently of the power of the other spring. It is obvious that in the device described the choice of the shape of the profiled edge 8 permits of perfectly controlling the movement of the auxiliary lever 7, and hence the retracting movement of the lever 4. This retracting movement may therefore be brought about slowly, rapidly or suddenly. The energy required for moving back the lever 4 is supplied by the spring 12. It may be accumulated in it along practically the entire path which the auxiliary member traverses between two points in which the lever 7 must be caused to become operative. If desired, the auxiliary member 9 may be coupled or rigidly connected to the component member 1. In the example shown, the directions of movement the A and B were parallel and opposite. As a matter of course, this is not essential.

In the form of construction of a device according to the invention shown in Fig. 4 the component member 20 and the auxiliary member 21 may be constructed as cam discs and both secured to the rotatable shaft 22. In this case, the rotation is effected in the direction of the arrow C, the lever 23 and the auxiliary lever 24 are rotatable about the same spindle 25 and in the case of continued rotation in an anti-clockwise direction the auxiliary lever carries the lever 23 along with it by means of a stop 26. The operation of the mechanism is as follows:

On rotation of the spindle 22, and hence of the

contact disc 20, the portion 27 of the profiled edge 28 gets under the end 29 of the lever 23 and under the action of the spring 30 the lever 23 performs a sudden movement about the spindle 25 in a clockwise direction until the stop 26 engages the lever 24. The clip formed by the levers 23, 24 and the stop 26 is then kept closed by the spring 30. Obviously, the depth of the recess 27 is unimportant because the movement of the lever 23 is limited by the stop 26 before the end 29 reaches the bottom of the recess 27. If the spindle 22 is then rotated further, the end 31 of the auxiliary lever 24 will, under the action of the spring 32, fall into the re-entrant part of 33 of the profiled edge 34 of the cam disc 21. Thus, however, the auxiliary lever 24 moves the lever 23 into its original position by means of the stop 26. On further rotation of the discs 20 and 21 the auxiliary lever 24 is moved into its off-position and the spring 32 is stressed under the action of the sloping part 34 at the edge of the contact disc 21. Since by this time the end 29 has again passed by the recess 27 it is impossible for the lever 23 to follow the said movement of the auxiliary lever 24. The clip is thus opened and the spring 30 is stressed. On continued rotation of the spindle 22 the springs 30 and 32 are therefore stressed at the same time due to the end 31 of the lever 24 riding up on the slope 34. As may be seen, this slope may extend without difficulty along substantially the entire circumference of the contact disc 21, that is to say that the supply of energy by the spindle 22 to the springs 30 and 32 is permitted by a very low supplementary couple on the driven shaft 22. The lever 23 may for example have connected to it an electric contact and the latter is, for example, suddenly opened and subsequently suddenly closed during a continuous rotation of the shaft 22. These two movements of the lever 23 may ensue without difficulty in very short sequence with each other. This is enabled by the fact that the energy required for the movement of the lever and the contacts that may be connected to it is supplied beforehand, during the entire revolution of the spindle 22 and hence during the period of rest of the lever 23, to the springs 30 and 32 in which it is accumulated.

Fig. 5 shows a slightly modified form of the construction shown in Fig. 4. In this case the end 49 of the lever 42 is beveled. Similarly, the re-entrant part 41 of the profiled edge 43 of the contact disc 44 is provided with a sloped portion 45. The cam disc 44 is rigidly connected with the auxiliary cam disc 49 and in contrast to the embodiments shown in Figure 4, these discs are loosely mounted on the driving spindle 46. Both discs are rotated in the direction of the arrow D by means of the spindle 46 through the intermediary of a crank 47 secured to the spindle and a catch 48 mounted on the cam disc 44. When the beginning of the sloped portion 45 has got under the end 49 of the lever 42, the cam disc 44, as well as the cam disc 49 connected therewith, is moved further by the lever 42 in the direction of the arrow D under the action of the spring 50, independently of the movement of the spindle 46. The arrangement is such that the end 51 of the auxiliary lever 52 will fall into the re-entrant part 53 of the profiled edge of the disc 49 before the rotation of the contact discs caused by the lever 42 has come to an end. Thus, the lever 42 is moved back into its original position by the auxiliary lever 52 under the action of the spring 54 and the stop 55. In direct sequence, the lever

42 consequently moves in a clockwise direction out of its off-position and in the opposite direction back into its off-position. Obviously it is impossible to stop the shaft 46 in such position that the lever 42 remains permanently in the recess 41 of the cam disc 44. In whatever position the spindle 46 is stopped, the lever 42 will always finally occupy its off-position. This mechanism may be nicely made use of in an automatic registering device, a so-called writer, in which the pointer of a sensitive measuring instrument carries a drawing stylus which is periodically forced on to a registering strip. This forcing should be effected for a short period only because the movement of the measuring device would otherwise be entirely interfered with. If the writing arm is desired to be mechanically driven, the mechanism has to satisfy the requirement that the writing arm can never keep on occupying its depressed position. For this purpose, the writing arm may be ganged to the lever 42 shown in Fig. 5 in such a way that upon movement of the lever end 42 into the recess 41 the drawing stylus is pressed on the registering strip and immediately thereafter, when lever 42 is lifted out of the re-entrant part 41 by means of the auxiliary lever 52 and stop 55, thus leaving the drawing stylus free of the registering strip again.

Fig. 6 shows a diagram of an electric device for checking the rotation of a shaft. In transmitters and electric devices of this kind a relay may have to remain closed so long as a certain shaft rotates. When the latter is stationary the relay is to be opened. A solution thereof is the following: The shaft has connected to it a make and break-contact. During rotation of the shaft this contact connects the condenser 60 to the battery 61 for a short period during each revolution. The condenser 60 thus becomes charged up. The coil 62 of the relay is connected in series with a resistance 63 to the condenser 60 and as long as the condenser is charged the relay remains energized.

The device is so proportioned that on rotation of the shaft the condenser 60 remains continually charged up. The switch 64 may be constituted with advantage by a set of electrical contacts actuated by the lever 42 of a device as shown in Fig. 5, the spindle 46 of which is driven by the shaft to be checked. The arrangement of the cam 44, the electrical contacts 64 and the lever 42 is such, that these contacts 64 are closed only when the lever 42 is lifted out of the recess 41 by means of the lever 52. This ensures that when the shaft to be checked is stationary, the contacts 64 are always in the open position. This obviates the difficulty encountered in the use of a normal sliding contact of the shack to be checked. In the latter case the shaft might happen to be stopped in a position in which the sliding contact is closed, thus keeping the condenser charged and the relay energized notwithstanding the fact that the shaft does not rotate any more. This would cause the relay to remain closed in spite of the shaft being stationary. The use of the construction shown in Fig. 5 avoids this erroneous indication.

The device described may be used with advantage for the intermittent drive of a shaft by a continuously rotating shaft, the coupling between the two shafts being operated by a cam acted upon in accordance with the invention.

What I claim is:

1. A device comprising a pair of discs each having a camming surface, said discs being rig-

idly interconnected for common rotative movement about their axes, a rotatable shaft, an abutment on one of said discs, means fixedly mounted on said shaft for rotation therewith and which may freely contact said abutment whereby rotation of said shaft, when said means and said abutment are in contacting relationship, will cause rotation of said interconnected pair of discs about their axes, but said pair of discs may move together freely ahead of said means, a first lug, means biasing said lug to bear against one of said camming surfaces whereby said lug normally follows the contour of said camming surface by moving in a direction substantially towards and away from the axis of its respective disc, a second lug, second means biasing said second lug to bear against said other of said camming surfaces whereby said second lug normally follows the contour of said second camming surface by moving in a direction substantially towards and away from the axis of its respective disc, said second biasing means having a greater strength than said first biasing means, engagement means for said lugs which are operable to cause said first lug to be moved in a direction away from the axis of its respective disc, whenever said second lug in following the contour of said other of said camming surfaces moves a predetermined distance in a direction towards the axis of its respective disc, said two camming surfaces having contours so related that said first lug bears against a portion of said one of said camming surfaces which causes said lug to move in a direction towards the axis of its respective disc before said second lug bears against a second portion of said other of said camming surfaces which causes said second lug to move in a direction towards the axis of its respective disc, said first portion having a slope and length so that once said first lug bears on said first portion, said discs will be rotated by said first lug riding on said slope due to the force of said first biasing means until said second lug bears against said portion, even though said shaft may have stopped rotating at the time said first lug has approached said first portion.

2. A device comprising a pair of discs each having a camming surface, said discs being rigidly interconnected for common rotative movement about their axes, a rotatable shaft, an abutment on one of said discs and offset with respect to the axis thereof, crank means fixedly mounted on said shaft for rotation therewith and which may freely contact said abutment whereby rotation of said shaft, when said crank means and said abutment are in contacting relationship, will cause rotation of said interconnected pair of discs about their axes, but said pair of discs may move together freely ahead of said means, a first lug pivotally mounted on a spindle, means biasing said lug to bear against one of said camming surfaces whereby said lug normally follows the contour of said camming surface by moving in a direction substantially towards and away from the axis of its respective disc, a second lug pivotally mounted on said spindle, said biasing means comprising a spring interconnecting said lugs, second means biasing said second lug to bear against said other of said camming surfaces whereby said second lug normally follows the contour of said camming surface by moving in a direction substantially towards and away from the axis of its respective disc, said second biasing means comprising a spring connected to said sec-

ond lug and to a fixed mounting and having a greater strength than said first biasing means; engagement means for said lugs which are operable to cause said first lug to be moved in a direction away from the axis of its respective disc, whenever said second lug in following the contour of said other of said camming surfaces moves a predetermined distance in a direction towards the axis of its respective disc, said two camming surfaces having contours so related that said first lug bears against a portion of said one of said camming surfaces which causes said lug to move in a direction towards the axis of its respective disc before said second lug bears against a second portion of said other of said camming surfaces which causes said second lug to move in a direction towards the axis of its respective disc, said first portion having a slope and length so that once said first lug bears on said first portion, said

discs will be rotated by said first lug riding on said slope due to the force of said first biasing means until said second lug bears against said second portion, even though said shaft may have stopped rotating at the time said first lug has approached said first portion.
